(Cl. D81—10)

Des. 183,862

PAGE 2

FIG. 5.

Figure 1 is a front perspective view of a heating stove showing my new design;

Figure 2 is a side elevational view;

Figure 3 is a rear perspective view;

Figure 4 is a top plan view; and

Figure 5 is a cross-section on the line 5—5 of Fig. 4 looking in the direction of the arrows.

I claim:

The ornamental design for a heating stove, as shown.
